AUTOMATIC CONTROL FOR TABULATING MACHINES

Robert B. Herbert, Endicott, N. Y., assignor to
 International Business Machines Corporation,
 New York, N. Y., a corporation of New York

Application March 29, 1935, Serial No. 13,691

3 Claims. (Cl. 235—61.7)

This invention relates to accounting machines and more particularly to accounting machines of the perforated card controlled type. It is directed to improvements in tabulating machines of the type shown and described in the patent to G. F. Daly and J. E. Dayger, No. 1,954,041, granted April 10, 1934, and the patent to C. D. Lake and G. F. Daly, No. 1,976,617, granted October 9, 1934.

The present invention is a further improvement in such machines with a view to obtaining an increased efficiency and utility thereof.

It has for its principal object the elimination of a number of operating cycles of the machine where so-called single card groups are tabulated, that is, groups of cards having but a single record card devoted to a particular classification.

In the statistical work handled by tabulating machines in general, the record cards are arranged in groups, which are separately tabulated and the totals printed on a suitable report sheet. To effect this, the items carried by the individual cards of each group are entered into a single accumulator as the cards are successively analyzed. Upon a change in the group designation, the machine enters upon a total printing and reset cycle, during which the total of the group is read from the accumulator and the accumulator is reset or zeroized. This procedure is followed for every group regardless of the number of cards comprising it, so that where there is a so-called single card group, the single item is transferred from the card to an accumulator and from thence re-transferred to the report sheet, all of which requires one machine cycle for accumulator entry, a second cycle for the total printing operation, and further time is required for effecting resetting.

Where the number of single card groups is comparatively large, it is obvious that the efficient operation of the machine is considerably lessened due to the duplicate cycles necessary to record single group items. In Patent No. 1,954,041 it was proposed to eliminate the entry of single card group items and the additional operating cycle necessary to total print the same, by inserting in the groups of cards what is known as a group signal card. This card is inserted in advance of all so-called multiple card groups and its function is to call into operation the automatic control mechanism which functions to signal the end of the multiple card group and to initiate a total printing and resetting operation wherein the group total is printed. For certain classes of work, the insertion of these group signal cards is not advantageous, especially where the

file of cards is later to be used in other operations in which the group signal cards are not required, so that it is necessary to first remove them from the file.

A specific object of the invention, therefore, is to provide a machine incorporating the advantages obtained in a machine such as disclosed in the patent mentioned without necessitating the use of group signal cards. The invention is realized by providing an extra card analyzing station in advance of the normal analyzing stations by means of which a predetermination can be made of the kind of card group about to be sensed, that is, whether it is a single card group or a multiple card group.

A further object of the invention is to provide a pre-sensing station in existing tabulating machines in which the re-organization of existing arrangements is reduced to a minimum.

Various other objects and advantages of the invention will be obvious from the following particular description of one form of mechanism embodying the invention or from an inspection of the accompanying drawings; and the invention also constitutes certain new and useful features of construction and combination of parts hereinafter set forth and claimed.

In the drawings:

Fig. 1 is a wiring diagram of the electric circuits of the machine.

Fig. 2 is a diagrammatic representation of the card feeding and analyzing devices showing the location of the pre-sensing station.

Fig. 3 is a chart showing the coding arrangement employed in perforating group classification numbers.

Fig. 4 is a chart showing the timing of the electrical contact devices of the machine.

In Fig. 2 is shown diagrammatically the manner in which cards are advanced from the record magazine past the analyzing instrumentalities. The brushes UB and LB are those usually found in this type of machine. By means of the picker 10 and gearing generally designated 11 cards are fed singly past the upper brushes UB and exactly one machine cycle later past the lower brushes LB. The cards are arranged with the usual index point positions and the timing is such that as any index point position of a record card is at the lower brushes, the same index point position of the next following card will be at the upper brushes.

In advance of the upper brushes UB, is provided, for the purposes of the present invention, a pre-sensing brush station designated PB lo-

30

cated in advance of the brushes UB a distance equal to half the distance between brushes UB and LB so that when the "1" index point position of a record card is at the brushes UB, the "9" index point position of the next following card will be at the brushes PB; when the "0" position is at UB, the "8" position of the next card will be at PB, and so on.

In order to permit comparison of record cards 10 at stations UB and PB, the fields of the cards in which the to be compared classification data are perforated, are perforated in accordance with a code of the form shown in Fig. 3, wherein a "9" is represented by a perforation in the "6" and 15 "8" index point positions and also in the "12" and "0" positions; an "8" in the "7" and "8" positions and also in the "11" and "0" positions. In making use of this coding arrangement, the classification number relating to a particular card 20 is punched in duplicate in the record card, once in the positions "6" to "9" and again in the positions at the top of the card, "12" to "1". This manner of punching is illustrated in the cards of Fig. 2 where the lowest card is punched to 25 represent 5237, the center card with the number 5238, and the uppermost card also with the number 5238.

With this arrangement, it will be apparent that 30 as the index point positions "1" to "12" are analyzed at the brushes UB, the positions "9" to "6" are analyzed at the brushes PB and for any particular number, the corresponding code perforation will be simultaneously presented to the brushes UB and PB. It will also be observed in 35 connection with Fig. 2, that the spacing of the parts is such that the duplicate sets of perforations in a single card are also compared with one another; that is, as the field of perforations at the bottom of the card is passing the brushes UB, the field at the top of the card is passing the brushes PB, the "9" position being analyzed concurrently with the "1", the "8" with the "0", the "7" with the "11", and the "6" with the "12". No actual comparison will be made between the two fields of the same card, however, since current is not supplied 40 to the brushes at such time.

The manner in which the brush stations LB, 45 UB, and PB control the operation of the machine will now be explained in connection with the circuit diagram (Fig. 1) wherein the brushes LB, which sense the data to be added and printed, are connected as representatively indicated by a plug connection 12 to the central blade of a pair of contacts 13a, 13b. These contacts are normally in 50 the position shown with contacts 13a open and from the open side a plug connection 16 is extended to a plug socket 17, while the closed contact is connected through a plug connection 14 to a plug socket 15. Socket 15 is connected to the printing magnet 19 through relay contacts 50a while the socket 17 is connected to an adding magnet 18.

The specific mechanism controlled by these 55 magnets does not per se form any part of the present invention and the illustration thereof is not deemed necessary. Reference may be had to Patent No. 1,976,617 for details of construction. Suffice it to say for the present purposes, that energization of magnet 18 will effect operation of the accumulating mechanism to add the amounts sensed by the brushes LB and the magnets 19 will 60 control printing of the same amounts.

During total printing operations, the readout mechanism of the accumulator, which is generally designated at 20, is adapted to complete cir-

cuits under control of an emitter 21 through contacts 22a which are closed during total printing operations so that the total of the amounts accumulated may be printed by the magnets 19. These printing, adding and total printing operations of the machine are well known to those familiar with the art and their detailed description is accordingly not given.

The brushes PB which traverse the coded fields of the cards are connected through plug connections 23 to plug sockets 24 which extend to one coil of a differentially wound relay magnet 25 and the corresponding brush UB is connected by plug connection 26 to a socket 27 extending to the other, oppositely wound coil of the magnet 25. It will 15 thus be apparent that if current flows through corresponding brushes UB and PB at the same time, the oppositely wound coils will oppose each other and the magnet 25 will have no effect on its normally closed contacts 28a. If, however, the 20 circuit passes through one of the brushes, the relay will become unbalanced and its associated contacts will be opened, thus indicating a disagreement in the perforations sensed by the brushes.

The current to brushes PB and UB is controlled 25 through cam contacts L8 and L10, which, as indicated in Fig. 4, are closed only during the period when the index point positions "1" to "12" are at the upper brushes so that the index point positions "5" to "2" in the coded section of the card are not 30 sensed by the brushes PB which will be traversing the space between cards when these unsensed positions are passing the brushes UB. Current is supplied to the brushes LB for the usual period; that is, while all the index point positions of the 35 card are traversing the brushes. The current is supplied from line 28, through lower card lever contacts 29, impulse distributing contacts 30, card lever relay contacts 31, to the brushes LB, so that as long as cards are passing the brushes, current 40 will be supplied to the contact roller thereof.

The contacts 28a are connected to plug sockets 33, any one of which may be connected through a suitable plug connection 34 to a socket 35. With this arrangement, any number of the contacts 28a 45 may be grouped in accordance with the number of positions in the coded field being sensed. In Fig. 1, the connection is made from the uppermost socket 33 so that the four contacts 28a are included in a series circuit. When all the contacts 50 28a are closed, a circuit may be traced from line 28, through wire 36, contacts 28a in series, connection 34, through relay contacts 37a (if these are closed), relay magnet 37, to line 38.

Relay magnet 37 is energized through cam contacts L11 which, according to Fig. 4, are closed for a short period at the beginning of each cycle, so that the circuit extending from line 28, through wire 36, contacts L11, relay magnet 37, to line 38, will maintain magnet 37 energized for the period 60 indicated on the timing chart and it is the function of contacts 28a and the circuit traced therethrough to maintain relay magnet 37 energized over the period that contacts L11 are open. With relay 37 energized, contacts 37b will also be closed 65 and a circuit may then be completed under control of cam contacts L12 near the end of the cycle to energize relay magnet 38, which in turn closes its contacts 39a, 39b, and 39c. Contacts 39a provide a holding circuit through cam contacts L13, 70 which, according to Fig. 4, pick up the circuit established by contacts L12 and hold magnet 38 energized for almost a complete cycle from the time of energization thereof.

As long as single card groups are passing 75

through the machine, one or more of the contacts 25a will be opened and the circuit through magnet 37 will not be maintained but will be broken at some point before contacts L12 close. Consequently, relay magnet 39 will not be energized.

If only single card groups are presented, the series circuit will be broken each cycle, and the lower brushes LB will remain in connection with the printing magnets 19.

Assuming now that the lower field of the record card of a multiple card group is about to pass brushes PB and the upper field of the preceding card of the same group is about to pass the brushes UB (see Fig. 2). The two fields about to be compared will register agreement and none of the contacts 25a will open, thus permitting the completion and maintenance of the circuit through magnet 39, traced above.

Closure of contacts 39c will complete the circuit from line 38, magnet 40, contacts 39c, switch 51, wire 36, to line 28. Magnet 40 closes its contacts 40a to permit completion of a holding circuit for the magnet through contacts P8 which are normally closed and open during the reset cycle.

Near the end of the cycle, as the first card of the multiple card group is about to pass the lower brushes LB, cam contacts L18 close, establishing a circuit from line 38, relay magnet 13, contacts L18, contacts 40a, contacts P8, wire 36, to line 28. Magnet 13 closes its contacts 13c to provide a holding circuit traceable from line 38, magnet 13, contacts 13c, contacts 40a and P8, wire 36 to line 28. Thus magnets 40 and 13 once having been energized will remain so until a total taking and reset cycle takes place during which contacts P8 in the holding circuits open. Magnet 13 also closes its contacts 13a and opens its contacts 13b thereby connecting the brushes LB to the adding magnets 18 and disconnecting the brushes from the printing magnets 19 so that as the first card of the group passes the lower brushes, the amount thereon will be added and not printed. As long as cards of the same group continue to be presented, magnets 37, 39, 40, and 13 continue to be energized and adding without printing will take place for each card of the group.

After magnet 13 is energized, a circuit is completed during the following cycle from line 38, magnets 41 and 50 in parallel, contacts L19, 13c, 40a, P8 and wire 36, to line 28. Magnet 50 closes contacts 50c to provide a holding circuit through contacts P9. Magnet 41 corresponds to magnet 77 of Patent No. 1,954,041, and functions to cause the uncoupling of the printing mechanism from the drive of the machine while the amount on the cards of the multiple card group are being added.

Energization of magnet 50 opens its contacts 50a to disconnect printing magnet 19 from socket 15 and closes its contacts 50b to connect magnet 19 to another socket 15b which is plug connected to a socket 15c thus conditioning circuit connections through which the total in the accumulator may be printed.

The machine will now continue running until a group change occurs; that is, until a card with a different group number arrives at brushes PB. The circuit which maintains the machine in operation is traceable from line 38, contacts P1, main clutch magnet 42, relay 43 (whose contacts 43a complete the circuit of motor TM), relay 44, contacts 44a, 44b, stop key contacts SP, contacts 45a switch 46, to line 28. This circuit is initially established as follows: on the usual preliminary

reset cycle initiated by closure of contacts ST2, a circuit is completed from line 38, contacts P3, reset clutch magnet 47, contacts L4, ST2, and 45b, switch 46, to line 28. The machine performs a resetting cycle of operations to clear the accumulators and during this cycle the so-called "P" cams rotate. Of these, contacts P6 complete a circuit from line 38, relay magnet 48, contacts P6, relay magnet 45, switch 49, contacts L8, to line 28. Magnet 48 closes its contacts 48a to 10 establish a holding circuit which is maintained until contacts L8 open. Energization of magnet 45 closes its contacts 45a so that at the end of the reset cycle when contacts P2 close, a circuit is traceable from line 28, switch 46, contacts 45a, 15 contacts SP, P2, the well known automatic start switch, relay magnet 44, contacts of magnet 42, magnet 42, contacts P1, to line 38. This is the well known automatic restart circuit which will permit establishment of the main operating circuit traced above.

A pair of normally closed contacts 13d short circuit contacts L8 and these remain closed until a multiple card group is sensed. They then open but since at such time magnet 39 is also energized as explained, a pair of contacts 39b closed thereby, establish a further short circuit. This circuit follows from line 28, wire 36, contacts 39b, magnet 45, contacts 48a, magnet 48, to line 38. 25

When the last card of the multiple card group 30 is at the upper brushes UB and a card with a different group number is at the brushes PB, relay magnet 39 becomes deenergized near the end of the cycle after contacts L8 have closed. The machine continues to run until the last card has 35 passed the lower brushes LB when contacts L8 open, deenergizing magnets 45 and 48. It will be noted as pointed out above that magnets 40 and 13 remain energized until the total taking 40 cycle takes place and contacts 13d are consequently open when contacts L8 open to deenergize the magnets 45 and 48. Consequent opening of contacts 45a breaks the main motor clutch circuit and contacts 45b establish the automatic reset circuit traceable from line 28, switch 46, 45 contacts 45b, switch S2, contacts L3, relay magnet 60, contacts P3, to line 38. Magnet 60 closes its contacts 60a setting up a circuit from line 28, contacts 60a, L4, magnet 47, contacts P3 to line 38. 50

The machine thereupon enters the usual total printing cycle during which the total of the group added is printed and the accumulator zeroized. During this cycle closure of contacts P6 again energizes relays 48 and 45 to reestablish the main 55 drive circuit and the machine will resume printing or adding accordingly as the next group is a single card group or a multiple card group.

If the next following group is a single card group, lack of comparison between it and the 60 next following card will have been detected as the last card of the foregoing multiple card group passed the lower brushes LB. During the total taking cycle just explained, therefore, relays 37 and 39 will remain deenergized and relay 40 will 65 become deenergized upon opening of contacts P8 near the end of the reset cycle. The circuit for magnet 13 is thus also broken so that upon resumption of card analyzing the single card group which is about to pass the lower brushes 70 is directly listed.

If the group following the total taking cycle is a multiple card group, the first two cards thereof will have been compared and found in agreement as the last card of the foregoing group 75

- passed the lower brushes LB. Magnets 37 and 39 would therefore have been energized and the latter held energized throughout the total taking cycle. Upon opening of contacts P8 the magnet 13 will not become deenergized since a circuit path is available through the now closed contacts 39c and switch 51. Accordingly upon resumption of card analyzing operations the data analyzed on the next group will be added without listing.
- 10 In this manner a form of presetting is made before the total taking operations take place, which determines the type of operation which is to follow after the completion of the total taking operations.
- 15 While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.
- 20
- 25 What is claimed is as follows:
1. In a machine of the class described, three sensing stations, means for feeding cards past said stations in succession, means controlled by the first two stations for determining whether the
  - 30 cards fed are of a single-card or multiple-card group, adding and listing control mechanism and

means controlled by said determining means for causing the third station to control either the adding or listing control mechanism accordingly as the cards sensed are of a multiple-card or single-card group.

2. In a machine of the class described, three sensing stations, means for feeding cards past said stations in succession, means jointly controlled by the first two stations for determining whether the cards fed are of a single-card or multiple-card group, recording mechanism, and means controlled by said determining means for causing the third station to control said recording mechanism in response to cards of only one of said types of card groups.

3. In a machine controlled by record cards arranged in single-card and multiple-card groups, three sensing stations, means for feeding cards past said stations in succession, printing control means, adding control means, means jointly controlled by a pair of said stations for detecting the presence of multiple-card groups, means normally connecting said printing control means with the third of said stations, and means controlled by said detecting means for connecting 25 said adding control means with said last named sensing station during the sensing of multiple-card groups and disconnecting the printing control means therefrom.

ROBERT B. HERBERT.
